F. L. FAIRBANKS

APPARATUS FOR TESTING VENTILATION

Filed March 14, 1925

FIG. 1.

Frank L. Fairbanks, INVENTOR

BY
Robert V. Moran, ATTORNEY

UNITED STATES PATENT OFFICE.

FRANK L. FAIRBANKS, OF ITHACA, NEW YORK.

APPARATUS FOR TESTING VENTILATION.

Application filed March 14, 1925. Serial No. 15,661.

This invention relates to the art of heating and ventilating, being a means for studying the movement of air current even when they are circulating slowly. More specifically, it is an improvement in the A. C. or ammonium chloride apparatus used by heating and ventilating engineers to produce a smoke by which currents of air may be traced. In the apparatus used in the past the smoke producing chemicals were combined by a pair of atomizers carried on the person of the operator and pumped by him when smoke was desired. This type of apparatus tended to become clogged by excessive production of the smoke particles at the nozzle, and required frequent cleaning. It was difficult to get a steady smoke of uniform density with such apparatus, and in addition the body of the operator cut off some of the air currents, while in the case of large cold buildings such as barns the heat from the operator's body impaired the results. The object of this invention is to provide an improved form of apparatus, which will not become clogged nor require frequent cleaning, and which is also self-acting and capable of being placed at a distance where the air currents may approach it from any direction undisturbed, while the apparatus gives an even and steady smoke production. Another object of the invention is to reduce the cost and complexity of such apparatus, so that it may come into more general use.

Referring now to the drawing, Fig. 1 illustrates in vertical cross-section one form of the apparatus. It consists of a bowl 1 provided with a cover 2, which may be lifted off. Within this bowl 1 is placed another bowl 3, which is provided with a removable cover 4. The inner bowl 3 is preferably somewhat lower than the outer bowl 1; but the bowl 3 may if desired be made the same height as the outer bowl 1, in which case a single lid may cover both; or a single watch glass may be curved to cover both in any case if desired. It is immaterial whether the two bowls 1 and 3 are integral with each other or separate, or whether the inner bowl is lower, level, or slightly higher than the outer bowl, though I believe it is preferable to have the inner bowl slightly lower than the outer one. But it is important that the outer bowl 1 should entirely encircle or extend around the inner bowl 3, in order that the continuity and uniformity of action should not be disturbed by changes in the direction of the air currents. For this reason round bowls are preferable, or at least bowls of substantially regular contour or pattern.

The operation is as follows:—A small quantity of HCl is poured in the bowl 3 and a small quantity of NH₄OH is poured in the bowl 1, or vice versa. The vapor given off spontaneously by the NH₄OH rises and combines with the vapor given off by the HCl to form a smoke which is given off so long as the chemicals remain. If it is desired to stop the operation before the chemicals are exhausted, the inner bowl is covered by the lid 4, or both bowls may be covered. I make no claim to the discovery of the chemical reaction, it being the same as in the prior apparatus mentioned; neither is my invention limited necessarily to these particular chemicals, as any chemicals whose vapor on combining produces a smoke might be used. My invention relates not to the chemicals, but to the apparatus in which the chemicals operate.

In the foregoing I have described the principles of my invention, and illustrated one embodiment in its preferred form. It will be understood that the invention is not limited to the particular form shown, as it may be applied with various modifications and adaptations as will be evident to those skilled in the art. The apparatus which has been used in the foregoing specification as a basis for explanation will be understood to be merely by way of illustration, whereas the essential features and combinations which constitute the invention are embodied in the following claims.

1. In a chemical smoke apparatus, the combination of a container for a volatile liquid, a volatile liquid in said container, a

second container, a second volatile liquid in said second container, said second volatile liquid being capable of forming a smoke in the presence of the first mentioned volatile liquid, said second container extending around on different sides of the first mentioned container, both containers being open at the top so that the vapors arising from the liquids below can commingle with substantially equal facility irrespective of the side from which the air currents come.

2. In a chemical smoke apparatus, the combination of a container for a volatile liquid, a volatile liquid in said container, a second container, a second volatile liquid in said second container, said second volatile liquid being capable of forming a smoke in the presence of the first mentioned volatile liquid, a cover for said first mentioned container, said second container extending around on different sides of the first mentioned container, both containers being open at the top so that when the cover is removed the vapors arising from the liquids below can commingle with substantially equal facility irrespective of the side from which the air currents come.

3. In a chemical smoke apparatus, the combination of a container for a volatile liquid, a volatile liquid in said container, a second container, a second volatile liquid in said second container, said second volatile liquid being capable of forming a smoke in the presence of the first mentioned volatile liquid, means for covering said containers, said second container extending around on different sides of the first mentioned container, both containers being open at the top so that when the covering means is removed the vapors arising from the liquids below can commingle with substantially equal facility irrespective of the side from which the air currents come.

4. In a chemical smoke apparatus, the combination of a bowl adapted to contain a volatile liquid, a volatile liquid in said bowl, a second bowl adapted to contain another volatile liquid, a second volatile liquid in said second bowl, said second volatile liquid being capable of forming a smoke in the presence of the first mentioned volatile liquid, said second bowl being located within the first mentioned bowl, the two bowls being open to each other and to the air above the level of the liquids in them, whereby the vapors arising from the liquids can commingle with substantially equal facility irrespective of the direction of the air currents passing over the bowls.

5. In a chemical smoke apparatus, the combination of a bowl adapted to contain a volatile liquid, a volatile liquid in said bowl, a second bowl adapted to contain another volatile liquid, a second volatile liquid in said second bowl, said second volatile liquid

being capable of forming a smoke in the presence of the first mentioned volatile liquid, said second bowl being located within the first mentioned bowl, the two bowls being open to each other and to the air above the level of the liquids in them, whereby the vapors arising from the liquids can commingle with substantially equal facility irrespective of the direction of the air currents passing over the bowls, and means for covering one of the bowls.

6. In a chemical smoke apparatus, the combination of a bowl adapted to contain a volatile liquid, a volatile liquid in said bowl, a second bowl adapted to contain another volatile liquid, a second volatile liquid in said second bowl, said second volatile liquid being capable of forming a smoke in the presence of the first mentioned volatile liquid, said second bowl being located within the first mentioned bowl, the two bowls being open to each other and to the air above the level of the liquids in them, whereby the vapors arising from the liquids can commingle with substantially equal facility irrespective of the direction of the air currents passing over the bowls, and means for covering the bowls.

7. In a chemical smoke apparatus, the combination of a container for a volatile liquid, a volatile liquid in said container, a second container, a second volatile liquid in said second container, said second volatile liquid being capable of forming a smoke in the presence of the first mentioned volatile liquid, said second container extending around on different sides of the first mentioned container, both containers being open to each other and to the air above the level of the liquids in them, so that the vapors arising from the liquids below can commingle with substantially equal facility irrespective of the direction of the air currents passing over the containers.

8. In a chemical smoke apparatus, the combination of a container for a volatile liquid, a volatile liquid in said container, a second container, a second volatile liquid in said second container, said second volatile liquid being capable of forming a smoke in the presence of the first mentioned volatile liquid, said second container extending around on different sides of the first mentioned container, both containers being open to each other and to the air above the level of the liquids in them, so that the vapors arising from the liquids below can commingle with substantially equal facility irrespective of the direction of the air currents passing over the containers, and means for covering one of the containers.

9. In a chemical smoke apparatus, the combination of a container for a volatile liquid, a volatile liquid in said container, a second container, a second volatile liquid in

said second container, said second volatile liquid being capable of forming a smoke in the presence of the first mentioned volatile liquid, said second container extending around on different sides of the first mentioned container, both containers being open to each other and to the air above the level of the liquids in them, so that the vapors arising from the liquids below can commingle with substantially equal facility irrespective of the direction of the air currents passing over the containers, and means for covering the containers.

In witness whereof I have hereunto set my hand this 24 day of Feb., 1925.

FRANK L. FAIRBANKS.
